TUBE MAKING MACHINE

Christian Majer, Tubingen-on-the-Neckar,
GermanyApplication July 23, 1938, Serial No. 220,936
In Germany July 29, 1937

7 Claims. (Cl. 271—27)

Rotating cylinders with stationary nozzles are known for sucking cut sheets from piles and for feeding them to devices on paper working machines for further treatment. These known arrangements are open to the objection, that, both the sucking and lifting of the paper sheet and also the delivering thereof is dependent upon predetermined distances, with the result that a perfect feeding of the blank is not ensured.

10 This objection is overcome by the machine according to the invention for lifting, pasting, conveying and delivering blanks to the working apparatus by means of suction air on paper working machines of all kinds, especially tube winding and packing machines. This machine is characterized in that on the periphery of a transporting element such as a drum, cylinder, segment or the like, which is rotatably or oscillatably mounted, one or more countersunk, outwardly 15 movable suction bars or the like are arranged which, when the transport means is at a standstill, move out of the periphery thereof and suck on the blanks, whereas the two or more additional bars deliver the blank for further treatment. After sucking and delivering the blanks, 20 the suction bars are moved back into the cylinder until they are flush with the periphery thereof. If, for example conical tubes are wound on the tube winding machine the suction bars must 25 be so mounted in the cylinder that they can assume an oblique position during the delivering of the blank to the winding mandrel. By this machine a reliable lifting and transporting of the blank from the pile and a reliable delivering 30 of the blank are attained.

35 The pasting mechanism with pasting roller is arranged on the periphery of the cylinder or the like in the direction of rotation in such a manner that the container with the pasting roller can be moved away from the cylinder after the 40 pasting of the blank.

An embodiment of the invention is illustrated in the accompanying drawings in which:

Fig. 1 shows the machine in front elevation,
15 Fig. 2 is a side elevation and
Fig. 3 a top plan view.

In the machine frame 1 a conveyor cylinder 3 is intermittently rotatable about an axle 4 mounted in bearings 2. The cylinder 3 has in its periphery recesses 5 in which outwardly shiftable suction bars 6 are arranged. The suction bars 6 have longitudinal bores 7 from which suction ports 8 extend. The longitudinal bores 7 of the suction bars 6 are connected by hose conduits 9 to a suction conduit 10 in the hollow shaft 4 of

the cylinder 3. Bars 13 are radially shiftable in guides 12 in the cylinder, and the suction bars 6 are oscillatable about pins 14 at the outer ends of these bars 13. The suction bars 6 are connected at one side of the pins 14 to tension springs 15 by means of which they are constantly pulled inwards. Arms 16 with guide rollers are mounted on the suction bars 6 at the other side of the pins 14, said rollers running on guides 17 and 18 during the up and down movement of the bars. During the suction period the suction bars 6 must be moved horizontally downwards. In this instance the guide surface 19 of the guide 17 is straight and vertical, whereas the guide surface 20 of the upper guide 18 is curved so that during its upward movement the upper suction bar 6 assumes an oblique position corresponding to the conical winding mandrel 21. The curved surface of the upper guide 18 depends upon the shape of the winding mandrel 21. The bars 13 are moved by two-armed levers 22 and 23 which are rocked by cams 24, 25. The bars 13 have pins 26 and 27 which, during the rotation of the cylinder 3 through an angle of about 180° engage in continuous slots 28 and 29 in the levers 22 and 23. As soon as the cylinder 2 has assumed this position, it remains stationary for a short time, whereupon the levers 22 and 23 are rocked, the lever 22 downwards and the lever 23 upwards with the result that the lower suction bar 6 is moved downwards and pressed against the upper blank 30 for suction. At the same time the upper suction bar is pushed upwards against the winding mandrel by the upward movement of the lever 23 and during this movement is moved past the cam 20 and thus assumes an oblique position corresponding to the conical winding mandrel 21 (Fig. 2). The levers 22 and 23 are acted upon by a spring 31, by means of which the arms 32 and 33 are pulled continually against the cams 24 and 25. After sucking up the uppermost blank from the pile 30 and the lifting and delivering of the preceding blank 34 to the winding mandrel 21, the suction bars 6 are returned, under the influence of the levers 22 and 23 and the springs 15, into their initial position in the recesses 5, in the cylinder 3, whereupon the cylinder 3 continues its rotation. The sucked up blank is then carried past the pasting roller 36 and smeared with paste. As soon as the cylinder has rotated through an angle of 180° and the lower suction bar 6 has been raised, the cycle of operation commences afresh, the lower bar 6 sucking up the uppermost blank from the pile 30 and the upper

bar delivering the preceding blank 34 to the winding mandrel.

The pasting roller 36 is rotatable in the paste container 37 which is fixed on an oscillatably mounted two-armed lever 38 actuated by an eccentric on the driven shaft 40 through the intermediary of a connecting rod 39. The paste container 37 is moved with the roller 36 in such a manner that the pasting roller 36 is pressed against the cylinder 3 as the blank 34 is being carried past the roller, and as soon as the blank has been pasted, the paste holder 37 is moved away from the cylinder 3 with the pasting roller 36. The cylinder 3 is of such a large diameter, and the pasting mechanism 36, 37 is so arranged in front of the cylinder 3 that, when the blank 34 has been brought under the winding mandrel 21, the blank 34 has left the pasting roller 36 (Fig. 1). At this moment the pasting mechanism 36, 37 is moved away from the cylinder 3. The paste container might be shiftable in guides instead of being oscillated. The whole machine is driven by a belt pulley 41, driving shaft 40 with the cams mounted thereon and by transmission wheels 42, 43, 44 and 45. A drum, disc or even segments might be used instead of the cylinder 3, and these might receive an oscillating instead of rotary movement. More than two suction bars 6 might also be provided. The winding mandrel 21 may be of any cross-section and shape, that is might be cylindrical, polygonal or the like. When using winding mandrels rotating in a horizontal plane for example cylindrical or square mandrels the suction bars 6 may be arranged horizontally fixed on the bars 13. In this construction the guides 17 and 18 may be omitted.

I claim:

1. In a machine for producing paper tubes from blanks heaped up in a pile, a device for lifting the actually uppermost blank from the pile of blanks, pasting said blank and delivering said pasted blank to the machine for further treatment, said device comprising in combination a conveying element having two recesses in its outer surface, two suction bars one shiftably mounted in each of said recesses and each adapted to suck-on the uppermost blank from the pile of blanks when the conveying element reaches and moves over said pile, a pasting roller in the path of movement of said uppermost blank in close proximity to the surface of said conveying element and adapted to paste said blank during the rotation of said element, and a winding device adapted to wind said pasted blank, and means for successively moving one of said bars outwards to deliver said pasted blank to said winding device at the moment the other bar is sucking a fresh blank from the pile.

2. In a machine as specified in claim 1, the means for shifting the suction bars comprising carrier bars carrying said suction bars, guides in the rotary element for said carrier bars, levers engaging said guides, and cams cooperating with said levers to rock said levers and radially shift said carrier bars and move said suction bars out of their recesses.

3. In a machine as specified in claim 1, the means for shifting the suction bars comprising carrier bars, each carrying one of said suction bars, guides for said carrier bars arranged in the rotary element, pins one projecting from each of said carrier bars, rocker levers having each a recess at one end adapted to engage one of said pins, and cams cooperating with the other end of said levers to oscillate said levers and to radially shift said carrier bars in said cylinder through the intermediary of said pins, and move said suction bars out of said recesses.

4. In a machine as specified in claim 1, the means for shifting the suction bars comprising carrier bars radially shiftable in the rotary conveyor element, means for radially shifting said carrier bars, pins pivotally connecting each of said suction bars to the outer end of one of said carrier bars, retracting springs one connected to each of said suction bars on one side of its pivot pin, and tending to return said suction bars into their recesses, arms one projecting inwardly from each of said suction bars on the opposite side of its pivot pin to its spring, rollers one on the inner end of each of said arms, and guides in said cylinders in the path of said rollers during the radial displacement of said carrier bars and adapted to control the movement of said suction bars through the intermediary of said arms.

5. In a machine as specified in claim 1, a pasting mechanism arranged near the periphery of the rotary element between the pile and the paper working tool, said rotary element being of such diameter and said pasting mechanism being so arranged that the blank has passed said pasting mechanism before delivering to said tool.

6. In a machine as specified in claim 1, a pasting mechanism arranged near the periphery of said rotary element between the pile and the paper working tool, and means for moving said mechanism alternately towards and away from said rotary element during the rotation of this element.

7. In a machine for producing paper tubes from blanks heaped up in a pile, a device for lifting the actually uppermost blank from the pile of blanks, pasting said blank and delivering said pasted blank to the machine for further treatment, said device comprising in combination a conveying element having at least one recess in its outer surface, a suction bar shiftably mounted in said recess adapted to suck-on the uppermost blank from the pile of blanks when the conveying element reaches and moves over said pile, a pasting roller in the path of movement of said uppermost blank in close proximity to the surface of said conveying element and adapted to paste said blank during the rotation of said element, and a winding device adapted to wind said pasted blank, and means for stopping said element after the pasting operation and for moving said bar outwards to deliver said pasted blank to said winding device.

CHRISTIAN MAJER.
